GERMINATION COVER FOR SEED BEDS AND THE LIKE

William H. Rand, Rte. 1, Box 195,
Battleground, Wash. 98604

Filed Oct. 5, 1967, Ser. No. 8,879

Term of patent 14 years

(Cl. D35—1)

FIG. 1

FIG. 2

FIG. 3

FIG. 1 is a perspective view of my germination cover for seed beds and the like in its operative position;

FIG. 2 is an elevational view of the right-hand end of the cover as the parts are shown in FIG. 1; and

FIG. 3 is a perspective view of the cover in its inverted position.

I claim:

The ornamental design for a germination cover for seed beds and the like, as shown.
